COMBINED BUMPER AND LAMP GUARD

Harry E. Williams and Lyndon A. Durant,
Chicago, Ill.

Application March 31, 1939, Serial No. 265,116

5 Claims. (Cl. 273—118)

This invention has as its principal object the provision of a combination bumper and lamp guard especially suitable for use in amusement apparatus in the nature of the pin ball or bagatelle game, the improved guard and bumper device being in the nature of a shell of a translucent material, preferably a thermoplastic, and adapted for mounting on a playboard or the like, with a lamp disposed therein to illuminate the shell, the shell being provided on its outer portions with springy means constituting a rebound bumper.

A further object is the provision of a combination bumper and lamp housing for use in amusement apparatus, and which comprises a cylindrical shell of translucent material which may be colored, said shell being substantially closed at one end and having its opposite free end disposed in a mounting member upon which is a lamp projecting into the shell to illuminate the latter in accordance with its particular coloring under certain circumstances, the shell having a rebound member removably embracing the same about its outer peripheral parts and serving to repulse or reproject a missile such as a ball.

Other objects, advantages, and economies residing in the invention will appear as the following description proceeds in view of the drawings, in which:

Fig. 1 is a top plan view of a fragment of a game board employing the improved bumper and lamp housing;

Fig. 2 is a fragmentary vertical section through the game along line 2—2 of Fig. 1;

Fig. 3 is a vertical section through the bumper and lamp housing, taken along line 3—3 of Fig. 1; while

Fig. 4 is a circuit diagram.

In one of its preferred forms, the novel device is constructed from a suitable thermoplastic material which lends itself readily to expeditious and economical molding and coloring, and comprises a cylindrical housing 10 having one axial end wall 11 which is substantially closed except for an air vent 12 and which is preferably of convex contour and constitutes a top for the housing.

The opposite or free end portion of the cylinder is reduced to provide a shoulder 13 and a seating shank 14 which fits into a seating opening in a mounting member such as the game board 15, so that the upper or main body portions of 55 the cylindrical housing are disposed on the upper

side of the board in substantially upright position relative thereto.

An electric lamp 20 (Fig. 3) mounted in a socket 21 on an arm 22 secured by screw means 23 to the under side of the board 15, is disposed 5 to project upwardly into the housing 10, and this lamp may be arranged in a circuit such as shown in Fig. 4, wherein the lamp is connected by a conductor 25 to one side of a battery 26, the opposite side of which battery is connected to a 10 switch 27 by a conductor 28 which in turn is connected to one contact 29 of a switch 30. The opposite contact 31 of switch 30 is connected by conductor 32 to the remaining terminal of the lamp. Thus, when the switches 27 and 30 are 15 closed, the lamp will be illuminated, and due to the translucent material of which the housing 10 is constructed, the latter will be attractively illuminated from within, the color of light emanating from the housing depending upon the pigment used in the thermoplastic. 20

In the illustrative circuit diagram of Fig. 4, the switch 30 is arranged to be operated by an electromagnet 35 having one of its terminals connected by conductor 36 to one terminal 37 of a 25 ball-operated switch 38, the other terminal of this switch being connected by a conductor 39 to one side of the battery. The remaining side of the battery is connected by a conductor 40 (assuming the master switch 27 to be closed) to one of the contacts 41 of a normally closed switch having a contact 42 which connects by a conductor 43 with the remaining terminal of the electromagnet. The armature 44 of the electromagnet is arranged normally to close the switch contacts 41—42 so that when the ball switch 38 is closed the magnet 35 will be energized and its armature pulled up to close contacts 29—31 of the lamp switch. 30 35 40

In the illustrative arrangement of Fig. 1, there are two lamp housings 10 and 10' in spaced relation on the board 15, and the ball switch 38 is mounted beneath the board and has a roll-over operating arm 34 which projects through an 45 opening 45 in the board for engagement by a ball or the like passing between the two lamp housings.

When a playing piece or ball is directed by skill or in some other manner so that it will pass between the lamp housings 10 and 10', switch 38 50 will be operated to cause the lamp 20 to flash. It is contemplated that a variety of control circuits other than that specifically described in conjunction with Fig. 4 may be utilized in various games, the lamps in the housings 10 and 10' in the 55

Illustrative arrangement being preferably operated by separate circuits and only one such circuit being illustrated for explanatory purposes.

Each of the housing members 10 is provided with rebound means in the preferred form of a band 50 of resilient material such as rubber, which is fitted around the shell at a predetermined level above the board 15 for engagement by a projectile or ball, the resiliency or springiness of the material of which the encircling rebound members or bands are formed being preferably adequate to throw the projectile back with a positive deflecting action.

In the illustrative embodiment, the rebound members 50 are in the preferred form of rings of rubber of circular cross section, and each of the shells or housing members is provided with formations or means providing a mounting for the rebound rings, this means being in the form of a channel 51 molded or turned into the outer periphery of the shell near the top. By this arrangement the bands may be quickly assembled at their proper positions relative to the top and skirt portion of the housing and will be secured against dislodgment by the impact of balls thereagainst.

In some circuit arrangements the lamps 20 are arranged for relatively constant illumination and will generate an appreciable amount of heat. The air circulating means or vents 12 in the crown of the housing permit egress of the warmer air and consequently stimulate movement of cooling air in the housing about the lamps.

Various changes and rearrangements may be made in the specific embodiment set forth in detail herein for purposes of illustration, and it is intended that the appended claims shall include all equivalent forms of construction and arrangement of parts which may be fairly embraced within the scope and spirit of the invention.

Having thus described our invention, what we claim as new and desire to protect by Letters Patent is:

1. A device of the class described including a shell of translucent material having reduced portions at one of its ends for seating in a mounting opening, said shell having groove portions about its outer periphery providing a mounting for a rebound member, and a rebound member in the form

of a ring of springy material fitted into said groove portions into gripping engagement with said shell, said shell being adapted to enclose an electric lamp.

2. A device of the class described comprising a unitary cylindrical shell of solidified translucent plastic material having a reduced shank portion adapted to fit into a mounting opening in a support, said shell having a circumferential channel formed in its outer periphery, and springy rebound means disposed in said channel so as to substantially encircle said shell, said shell constituting a housing for a light.

3. A device of the class described comprising a cylindrical shell of translucent material adapted to enclose a lamp having a reduced shank portion adapted to fit into a seating opening in a support and a circumferential channel arranged about its outer periphery between its ends, and a ring of springy material embracing said shell in said channel.

4. A device of the class described comprising a cylindrical shell of translucent material having a reduced portion at one of its axial ends and adapted to fit into a mounting opening in a support, the opposite axial end of said shell being closed and constituting a top therefor, said shell having a circumferential channel in its outer periphery between said top and shank, and rebound means encircling the shell in said channel, said shell being adapted to substantially enclose illuminating means on said support for illumination of the shell by light transmitted from within.

5. A combination bumper and lamp housing in the form of a cylindrical shell of translucent material having one of its axial ends closed to provide a top and having body portions adjacent its opposite open axial end reduced to provide a mounting shank which is adapted to be fitted into a mounting opening in a support, and a band of springy yieldable material extended about outer peripheral portions of the cylinder and constituting rebound means, said housing being adapted to enclose a lamp disposed therein through said open end for illumination of the shell from within.
